UNITED STATES PATENT OFFICE.

JOHN J. KENNEY, OF PITTSBURGH, PENNSYLVANIA.

THERMOSTATICALLY-ACTUATED VALVE.

Application filed May 12, 1926. Serial No. 108,534.

The present invention relates broadly to control valves, and more particularly to so-called quick-acting or snap action valves of the heat responsive or thermostatic type adapted to control the supply of gas or the like, although the utility of the invention is not limited with respect to the particular use to which it is placed or the type of fluid handled thereby.

10 At the present time there is a growing demand in the art for valves having the ability to move quickly from a full open to a full closed position. This is particularly true with installations using burners, such as Bunsen burners, in which there is a tendency toward flash back under certain conditions of fuel flow. Snap action valves of a more or less complicated and expensive nature have heretofore been designed for this purpose, and have been satisfactorily used to some extent, although in many cases the difficulty of accurate control has somewhat limited their use.

15 In my copending application, Serial No. 758,567, there is disclosed an improved type of valve of extremely simple construction and comprising a relatively small number of parts. The present invention embodies certain of the features therein disclosed and, 20 in addition thereto, means facilitating setting and operation of the valve.

25 In the accompanying drawings there is shown for purposes of illustration only, a preferred embodiment of the present invention, it being understood that the drawings do not define the limits of my invention as changes in the construction and operation disclosed therein may be made without departing either from the spirit of the invention or the scope of my broader claims.

30 In the drawings,

Figure 1 is a longitudinal sectional view through one form of valve embodying the present invention, the valve being shown 35 in closed position;

Figure 1^A is a view similar to Figure 1 showing the valve in open position;

Figure 2 is a vertical sectional view on the line II—II of Figure 1, and

Figure 3 is a transverse sectional view on the line III—III of Figure 2.

40 In carrying out the present invention there may be provided a valve casing 2 of any desired contour, but preferably so constructed as to provide therein an inlet passage 3 and an outlet passage 4. Intermedi-

ate the respective ports of these passages the casing may be provided with a valve seat 5 for a valve 6 which is preferably normally urged against the seat in suitable manner 45 as by a spring 7. The top of the casing is closed by a removable cap 9 having formed therein a central opening 10 through which extends a shaft 11 carrying on its upper end an actuating dial 12. The dial is preferably 50 provided on its periphery with a series of graduations 13 adapted to cooperate with a suitable indexing or marking pointer or projection 14 on the casing. At its lower end the shaft 11 carries a cup 15 eccentrically 55 disposed with respect to the axis of rotation of the shaft, whereby rotation of the dial will be effective for changing the relationship between the interior side walls of the cup shaped projection 15 and the cylindrical 60 boss 16 projecting upwardly from the valve. This boss preferably projects a considerable distance into the eccentric cup or sleeve, and is preferably of enough smaller diameter 65 than the interior diameter of the sleeve to 60 permit, not only easy entrance as set forth, but also to permit rotation of the sleeve. The spring 7 may be located within the sleeve 15 and may project at one end against the bottom thereof and at the opposite end 70 against the top of the boss 16.

65 Extending outwardly from one side of the casing is an externally threaded projection 17 permitting the casing to be secured to a suitable support. This projection has a 70 longitudinal bore extending therethrough and through a thickened portion of the wall of the valve casing, the outer casing of the bore conveniently being screw threaded for the attachment of the tubular expandable 75 member 18 of the thermostatic element. Located within the expandable member, in known manner, is the usual non-expansive element 19 such as porcelain, carbon or the like. The non-expansive element may abut 80 at its outer end against a cap 20 secured to the expandable member, while at its inner end it abuts against a thrust pin 21 sliding in the bore of the projection 17. This thrust pin may, if desired, be formed with 85 sealing grooves around its periphery, whereby it forms a gas tight joint between the interior of the valve casing and the interior of the expandable member 18.

90 A valve operating lever 22 may be extended vertically in the casing and have a suitable mounting therein such as indicated

by the oppositely projecting trunnions 23 adjacent its lower end indicated as bearing on an annular ledge 24 formed in the lower portion of the casing. The pin 21, preferably 5 has its inner end bevelled to a knife edge adapted to engage a shallow transverse groove 25 in one face of the lever 22, said knife edge lying in a horizontal plane slightly above the axis of the trunnions 23. 10 A screw threaded fulcrum 26 may be adjustably mounted in a threaded bore in the thickened portion of the wall of the valve casing diametrically opposite the bore in which is mounted the pin 21. This fulcrum 15 carries a pin 26' mounted with a loose fit in a socket in its inner end, which pin is cone shaped at one end to engage in a shallow recess 27 in the face of the lever 22 opposite the face containing the shallow groove 25, 20 the point of the pin 26' lying in a horizontal plane slightly below the axis of the trunnions 23. This loose fitting pin permits the valve operating lever to oscillate without undue friction or binding between the trunnions 23 and the seat 24, and also facilitates 25 assembly without necessitating absolute accuracy in machining of the parts.

The lever 22 has its upper end extending within the hollow boss 16 of the valve and 30 has a portion of its upper end shaped to provide an inclined bearing surface 28 with which cooperates a downwardly projecting stem 29 formed on the under surface of the boss 16. Adjacent the inclined portion 28 of 35 the lever 22, there is formed a flat seating surface 31 adapted to receive the stem 29 under predetermined conditions of operation as hereinafter set forth.

The lever 22 is also formed adjacent its 40 upper end with a stud 32 projecting a suitable distance from the face of the lever, preferably substantially in alignment with a similar stud 33 on the inner wall of the casing whereby the studs are adapted to receive and support a coil spring 34 normally 45 acting on the lever 22 in such manner as to tend to swing it in a counter-clockwise direction about the knife edge of the pin 21, as viewed, for example, in Figure 1 of the 50 drawings.

When the valve is closed, the normal position of the parts will be as indicated in Figure 1. The trunnions 23, resting on the ledge 24, support the weight of the lever and take 55 any downward thrust thereon due to the pressure of the valve on its upper end.

It will thus be seen that the point of the pin 26' and the knife edge of the thrust pin 21 are not subjected to any downward pressure 60 transmitted through the lever 22.

When the expansible member 18 of the thermostat contracts, the pin 21 will be forced to the right, as viewed in Figure 1 of the drawings, thereby causing the lever 22 to 65 rock in a clockwise direction about the point

of the pin 26' as a fulcrum. Due to the relative lengths of the lever arms, a comparatively slight movement of the pin 21 will result in a much greater movement of the upper end of the valve operating lever. The 70 first portion of this movement causes the valve 6 to slide bodily on its seat 5 until the boss 16 contacts with the side *a* of the sleeve 15, such contact preventing any further bodily lateral movement of the valve. The 75 valve lever 22, however, continues its movement under the influence of the thermostatic control, and gradually builds up an increasing pressure between the stem 29 and the incline 28. This condition continues until the 80 pressure is sufficient to overcome the friction between these parts plus the action of the spring 7, whereupon the valve 6 snaps vertically from its seat as will be clearly apparent, the stem 29 positioning itself upon 85 the flat upper portion 31 of the valve lever as indicated, for example, in Figure 1^A of the drawings. The valve will remain in its open position of this figure until the desired 90 temperature has been attained in accordance with the setting of the thermostat. Thereafter, any further increase in the temperature will cause expansion of the member 18, thereby permitting the spring 34 to rock the valve lever 22 to the left or in a counter-clockwise direction, as viewed in Figure 1 of the drawings, about the point of the pin 26' as a fulcrum, said lever forcing the thrust pin into the bore of the projection 17. The 95 first part of this counter-clockwise movement of the valve lever will result in a bodily lateral movement of the valve to the left, as viewed in Figure 1^A of the drawings, due to the friction between the stem 29 and the 100 end of the valve lever until such time as 105 the boss 16 engages the left hand side *b* of the sleeve 15, thereby stopping further movement of the valve. Thereafter, continued counter-clockwise movement of the lever 22 will result in relative movement between 110 the lever and the valve to establish a condition in which the action of the spring 7, in combination with the character of the contacting surfaces between the valve and lever 115 causes the valve to move bodily to the right as viewed in Figure 1^A and downwardly onto its seat with a snap action.

It will be appreciated that the valve, when in its closed position, can slide at will, on its seat within predetermined limits as permitted by the difference between the external diameter of the boss 16 and the internal diameter of the sleeve 15. Similar movement of the valve with the lever 22 is permitted also when the valve is in open position. This lost motion is provided in order to allow the valve to remain in either its closed or its open position through a suitable working temperature range. When the 125 valve is closed, it will assume some normal 130

intermediate position, such as indicated in Figure 1, and will slide back and forth on its seat as long as the temperature remains within such working range. This movement or lost motion further facilitates the operation of the valve in that it permits the building up of a force capable of overcoming the inertia of the valve and the consequent quick or snap movement thereof to the desired position.

With a given setting of the thermostat it may be desired, under certain conditions, to vary the effective temperature range within which the valve remains either in its open or its closed position. In the construction herein illustrated this may be easily accomplished by the mounting of the sleeve 15 eccentrically on its operating shaft 10, inasmuch as rotation of the dial 12 under such conditions will result in varying the dimensional change in the heat responsive means required for operating the valve. Due to the location of the dial, it is readily accessible, thereby permitting the desired adjustment to be quickly made.

It will also be understood that it is necessary, irrespective of the temperature range within which the valve operates, to provide effective means for varying the setting of the thermostat. This may be accomplished by adjusting the fulcrum pin 26'. To that end, the fulcrum pin may be provided on its outer end with a disk-like head 35 having a handle 36, whereby the pin may be easily turned. On this head there may be placed suitable indicating means adapted for cooperation with graduations on the valve casing. The adjustment for the fulcrum pin may be protected by providing a threaded extension on the valve casing adapted to receive an enclosing cap 37. By removing this cap, the desired adjustment of the thermostat may be quickly effected.

In my copending application referred to, I have claimed broadly the mechanism by means of which the snap action of the valve is obtained, the claims of the present application being directed particularly to a snap action valve having, for example, the characteristics referred to and provided with means whereby the effective temperature range may be easily adjusted irrespective of the setting of the thermostat.

From the foregoing it will be apparent that the present construction provides a valve having a stem which constitutes, in effect, an operating cam, with which cooperates a lever constituting an operating member. The construction is such that initially there is a simultaneous movement between the operating member with its cam and the operating cam on the valve, this simultaneous movement being in a lateral direction as et forth. Thereafter, the simultaneous movement ceases and a relative

movement occurs due to the cooperative action of the cams. The eccentric varies the amount of simultaneous movement and thereby enables accurate control of the period at which relative movement occurs. Inasmuch as the relative movement is responsible for either permitting or cutting off the flow of the fluid being controlled, such adjustment will, as pointed out, determine the effective range within which the valve will remain either in open position or in closed position.

In many ranges it is desirable to provide a valve of such nature that the oven temperature may be easily and quickly controlled and also varied at will within comparatively wide limits. The present valve, whether constructed to operate as a snap action valve or as a slow operating valve of ordinary characteristics, may be easily adjusted to vary the temperatures at which the opening and closing movements are effected while maintaining a substantially constant range required for the change from closed to open position or vice versa.

Certain advantages of the present invention arise from the combination with a snap action valve, of means whereby the range within which the valve is effective either for permitting flow of the fluid or for cutting off such flow, may be varied at will.

Still other advantages of the invention arise from the combination of a regulating valve which, if desired, may be of the snap action type with means for adjusting not only its effective temperature range but also the initial setting by means of which one limit of such range is determined.

I claim:

1. In a valve mechanism, a valve casing having a seat, a valve cooperating with said seat, a valve operating lever, a fulcrum operatively associated with said lever adjacent one end thereof, a heat responsive means effective on said lever, means for moving said lever in opposition to said heat responsive means, a hollow boss on said valve into which the other end of said lever projects, said boss having a stem projecting therefrom and said last mentioned end of the lever having a cam surface cooperating with said stem, a sleeve within which said boss projects and having a greater internal diameter than the external diameter of said boss, means for varying the effective position of said sleeve, and means normally urging said valve toward its seat.

2. In a valve mechanism, a valve casing having a seat, a valve cooperating with said seat, a valve operating lever, a fulcrum operatively associated with said lever adjacent one end thereof, a heat responsive means effective on said lever, means for moving said lever in opposition to said heat responsive means, a hollow boss on said valve into

- which the other end of said lever projects, said boss having a stem projecting therefrom and said last mentioned end of the lever having a cam surface cooperating with said stem, an eccentric sleeve within which said boss projects and having a greater internal diameter than the external diameter of said boss, means for adjusting the position of said sleeve, and means normally urging said valve toward its seat.
3. In a valve mechanism, a casing, a valve having an operating cam movable in either of two directions, an operating member for said valve having a cam cooperating with said operating cam, means for moving said operating member to effect bodily movement of said operating cam first in one direction and then in another direction, and means for varying, at will, the extent of said first mentioned bodily movement.
4. In a valve mechanism, a casing, a valve having an operating cam movable in either of two directions, an operating member for said valve having a cam cooperating with said operating cam, means for moving said operating member to effect bodily movement of the operating cam, first in one direction and then in another direction, and adjustable means eccentrically cooperating with said valve for varying the conditions under which said operating member will become effective.
5. In a valve mechanism, a casing, a valve having an operating cam movable in either of two directions, an operating member for said valve having a cam cooperating with said operating cam, heat responsive means for moving said operating member to effect bodily movement of said operating cam, first in one direction and then in another direction, and means for varying, at will, the temperature range of said first mentioned bodily movement.
6. In a valve mechanism, a casing, a valve having an operating cam movable in either of two directions, an operating member for said valve having a cam cooperating with said operating cam, heat responsive means for moving said operating member to effect bodily movement of the operating cam, first in one direction and then in another direction and adjustable means eccentrically cooperating with said valve for varying the conditions under which said operating member will become effective.
7. In a valve mechanism, a casing, a valve normally tending to move in one direction and having an operating cam movable in either of two directions, an operating member for said valve having a cam cooperating with said operating cam, means for moving said operating member to effect bodily movement of the operating cam, first in one direction and then in another direction, and adjustable means for determining the temperature range within which said bodily movement takes place.
8. In a valve mechanism, a valve casing having a valve seat, a valve cooperating with said seat, a valve operating member, cam surfaces between said member and said valve, means for moving said member to initially produce simultaneous movement of said cam surfaces and the relative movement thereof, and means for varying the position of said first mentioned movement to vary the period of relative movement between said cam surfaces.
9. In a valve mechanism, a valve casing having a valve seat, a valve cooperating with said seat, a valve operating member, cam surfaces between said member and said valve, heat responsive means for moving said member to initially produce simultaneous movement of said cam surfaces and the relative movement thereof, and means for varying the position of said first mentioned movement to vary the period of relative movement between said cam surfaces.
10. In a valve mechanism, a casing, a valve having an operating cam movable in either of two directions, an operating member for said valve having a cam cooperating with said operating cam, temperature responsive means for moving said operating member to effect bodily movement of the operating cam, first in one direction and then in another direction, means for varying the position at which movement in said first direction takes place, and means for varying the temperature at which said temperature responsive means becomes effective.
11. In a valve mechanism, a valve casing having a valve seat, a valve cooperating with said seat, a valve operating member, cam surfaces between said member and said valve, temperature responsive means for moving said member to initially produce simultaneous movement of said cam surfaces and the relative movement thereof, and means eccentric with said valve for varying the temperature at which said temperature responsive means becomes effective.
12. In a valve mechanism, a valve casing having a valve seat, a valve cooperating with said seat, a valve operating member, means for moving said member, cams between said member and said valve, whereby movements of said member are effective to operate said valve, one of said cams having an initial limited movement in one direction with the other and a limited movement in another direction relative to the other, whereby there is an initial lost motion between the cams, and means operable at will for varying the temperature at which said lost motion takes place.
13. In a valve mechanism, a valve casing having a valve seat, a valve cooperating with said seat, a valve operating member, temper-

ature responsive means for moving said member, cams between said member and said valve whereby movements of said member are effective to operate said valve, one of 5 said cams having an initial limited movement in one direction with the other and a limited movement in another direction relative to the other whereby there is an initial lost motion between the cams, and means operable at will for varying the temperature 10 at which said lost motion takes place.

14. In a valve mechanism, a valve casing having a valve seat, a valve cooperating with said seat, a valve operating lever, cam surfaces between said lever and said valve, heat responsive means for moving said lever to initially produce simultaneous movement of 15 said cam surfaces and the relative movement thereof, and means exteriorly of said casing 20 for varying the position of such simultaneous movement.

15. In a valve mechanism, a valve casing having a valve seat, a valve slidably cooperating with said seat, a heat responsive 25 valve operating member, there being a cam surface between said operating member and said valve, and means for varying at will the zone through which said valve is 30 slidable relatively to said seat.

16. In a valve mechanism, a casing, a valve having an operating cam, an operating member for said valve having a cam cooperating with said operating cam, means for moving said operating member to effect 35 bodily movement of the operating cam, and adjustable means eccentrically cooperating with said valve for varying the conditions under which said operating member will become effective.

17. In a valve mechanism, a casing having 40 a valve seat, a valve cooperating with said

seat, operating means for said valve, and adjusting means eccentrically cooperating with said valve for varying at will the time of operation thereof, said adjusting means 45 being capable of adjustment without moving said valve.

18. In a valve mechanism, a valve casing having a valve seat, a valve cooperating with said seat, a heat responsive valve operating means, and means eccentrically cooperating with said valve for varying the temperature at which said heat responsive means is operative, said last mentioned means being capable of adjustment without moving said 55 valve.

19. In a valve mechanism, a valve casing having a valve seat, a valve cooperating with said seat, a heat responsive valve operating member, there being a cam surface between 60 said operating member and said valve, and means for varying at will the effective relation between said operating member and cam surface, said last mentioned means eccentrically cooperating with said valve and 65 being capable of adjustment without moving said valve.

20. In a valve mechanism, a casing, a valve having an operating cam, an operating member for said valve having a cam cooperating 70 with said operating cam, means for moving said operating member to effect bodily movement of the operating cam, and adjustable means eccentrically cooperating with said valve and being capable of adjustment without moving said operating member, said operating member being controlled by temperature variations.

In testimony whereof I have hereunto set my hand.

JOHN J. KENNEY.
